VALVE CONNECTION SYSTEM

Heinrich Eberhard, Berlin, Germany

Application April 2, 1932, Serial No. 602,865
In Germany April 10, 1931

5 Claims. (Cl. 177—351)

The subject matter of the present invention relates to a novel valve connection system. The essence of the invention consists in doing away with a separate anode current source, and taking the energy for the anode circuit, through the medium of special connections, from the heating current source. Fundamentally, the invention relates to valve transmitters, valve receivers and other valve apparatus.

Particular advantages are disclosed by the arrangement according to the invention in connection with valve transmitters of the portable type. Owing to the fact that a separate anode battery is not required, it is possible to make use of valve transmitters for many new purposes, for instance for the recording transmitters carried by balloons, for patrol apparatus, etc.

The separate anode current source is now, according to the invention, eliminated by the fact that transformed energy for the anode circuit is taken from the heating current source by means of an induction coil arrangement. In its most elementary form this induction system consists of a vibrator with a transformer. For the operation of the vibrator a potential of roughly 2 volts is sufficient, i. e., the potential supplied by a chromic acid battery. Fundamentally, there is also the possibility of operating the vibrator by a special low-potential current source. The vibrator together with a suitable transformer readily supplies potentials up to several thousand volts, so that, for example, receiving and amplifying valves may be supplied with an anode potential amounting to 1000 volts and more without a special source of energy.

If the connection system according to the invention is employed for supplying anode potential to transmitter valves, the secondary winding of the vibrator transformer is connected in series with the oscillatory circuit through the medium of a transformer in the anode circuit.

The mode of operation of the arrangement according to the invention will be described with the assistance of the drawing. Thus, for example, in Fig. 1, *a* is the curve of the direct current, which is intermittent in rhythm with the interrupter (vibrator), and which, for example, may be assumed to traverse the primary circuit of the valve connection according to Fig. 2. It will be recognized that after applying the potential to the primary winding of the transformer the current rises following an *e*-function, remains for a moment practically constant, and upon disconnecting the anode potential, fol-

lowing an *e*-function, again drops to zero. The curve *b* in Fig. 1 shows the potential in the secondary winding of the transformer. Strong current impulses (*b'*) are to be recognized, which are produced by the breaking impulse of the primary circuit, and smaller impulses (*b''*), which correspond with the making impulse. The induction system is now connected with the anode circuit in such fashion that the breaking impulse causes a positive impulse, that is to say—in such fashion that the potential at the anode at this particular moment is positive in relation to the potential at the cathode. The negative half-wave of the making impulse is then suppressed owing to the unipolar conductivity of the valve.

In detail Fig. 2 shows the ionic valve 1 consisting of the cathode 2, the grid 3, the anode 4. The heating current source is designated 5, to which there is connected the primary winding 6 of the transformer 7 in series with the interrupter 8 (vibrator). The anode circuit comprises the secondary winding 9 of the transformer and an oscillatory circuit consisting of the condenser 10 and the coil 11.

If now under the influence of the breaking impulse a positive half-wave results in the anode circuit, there is superimposed to the increasing anode current (*b'*), which is represented on larger scale in Fig. 3, an oscillation, which commences at a certain minimum potential *c*, increases up to a certain maximum amplitude, and decreases along the sinking D. C. wave in accordance with the damping of the oscillatory circuit. The resulting high frequency oscillation possesses the periodicity of the oscillatory circuit 10, 11. Now this is by no means constant. The variable anode potential corresponds with a variable valve capacity in parallel with the oscillatory circuit. Consequently it is impossible to obtain with heterodyne reception a pure superposed tone from the transmitted wave. This may only be obtained by quartz control of the valve transmitter to be fed. For this purpose it is merely necessary in the case of the connection according to Fig. 2 to connect between the grid and the anode the piezo-electric crystal 12, the elastic natural vibration of which is identical with the natural frequency of the anodic oscillatory circuit 10, 11, and the choke 13, or a resistance. In Fig. 2, 14 is a bridging condenser for high frequency and 15 the anode.

The oscillation transmitted by a sender of this nature may now be picked up in faultless manner by a heterodyne receiver. The pitch of the 55

heterodyne tone corresponds in the known manner with the difference in frequency between transmitter and heterodyne oscillator. This tone is now intermittent in rhythm with the interrupter.

There is no objection to picking up a tone having the frequency of the interrupter. For this purpose it is merely necessary to pick up by means of a detector the one half wave from the 10 alternating current pulsating in rhythm with the piezo-electric control potential (Fig. 4).

If it is desired to feed amplifier and receiving valves with the arrangement according to the invention, it is necessary to connect a rectifier, 15 for example a tube valve, and if necessary one or more filter circuits in series with the secondary winding of the transformer and the oscillatory circuit.

If with the means according to the invention it 20 is desired to operate a telephonic transmitter, it is merely necessary to select ultra-sonorous interrupter frequency.

Insofar as the invention makes use of a vibrator, for instance for meteorological purposes, 25 in recording transmitters, the variation in the vibrator frequency itself may be utilized for recording a physical value. Thus, for example, it is possible to vary the vibrator tone accordingly, dependent on the degree of moisture. The variation in the tone of the vibrator may, in detail, 30 be so performed, for example, that the natural vibration of the tongue is varied by mechanical or magnetic means, or the magnetic field of the vibrator itself may be acted upon in suitable 35 fashion. This may be performed, for instance, according to the following method:

The thread of the hygrometer is secured to the tongue in such fashion that by reason of the variation in the length or the tension of the 40 thread corresponding action is exerted on the frequency of the vibrator.

Fundamentally, it is immaterial what physical value it is desired to transmit by variation of the vibrator frequency. Thus, for example, the embodiment of the arrangement may be such that with the same there may be measured the depth of water. For this purpose the recording transmitter would be fitted in a diving bell.

I claim:

50 1. In a signaling transmitter, a thermionic generator valve containing a cathode, grid and anode, a low voltage direct current source for the cathode, a transformer and an interrupter, means connected to said interrupter and controlled by a physical quantity for varying the interrupter frequency as a function of said physical quantity, circuit means including the interrupter for connecting the transformer primary to the low voltage source, thereby inducing 55 a voltage in the transformer secondary in accordance with said physical value, a high-frequency oscillatory circuit connected between the anode of the valve and said secondary means for controlling the frequency of said oscillatory circuit, and a transmitting circuit coupled to said oscillatory circuit, whereby the signal transmitted is controlled by said physical quantity.

2. In a signaling transmitter, a thermionic generator valve containing a cathode, grid and anode, a low voltage direct current source for the cathode, a transformer and an interrupter having an ultra-sonorous interrupter frequency,

means connected to said interrupter and controlled by a physical quantity for varying the interrupter frequency as a function of said physical quantity, circuit means including the interrupter for connecting the transformer primary to the low voltage source, thereby inducing a voltage in the transformer secondary in accordance with said physical value, a high-frequency oscillatory circuit connected between the anode of the valve and said secondary means for controlling the frequency of said oscillatory circuit, and a transmitting circuit coupled to said oscillatory circuit, whereby the signal transmitted is controlled by said physical quantity.

3. In a signaling transmitter, a thermionic generator valve containing a cathode, grid and anode, a low voltage direct current source for the cathode, a transformer and an interrupter, means connected to said interrupter and controlled by a physical quantity for varying the natural vibration frequency of the tongue of said interrupter as a function of said physical quantity, circuit means including the interrupter for connecting the transformer primary to the low voltage source, thereby inducing a voltage in the transformer secondary in accordance with said physical value, a high-frequency oscillatory circuit connected between the anode of the valve and said secondary means for controlling the frequency of said oscillatory circuit, and a transmitting circuit coupled to said oscillatory circuit, whereby the signal transmitted is controlled by said physical quantity.

4. In a signaling transmitter, a thermionic generator valve containing a cathode, grid and anode, a low voltage direct current source for the cathode, a transformer and an interrupter, means connected to said interrupter and controlled by a physical quantity for varying the magnetic field of said interrupter as a function of said physical quantity, circuit means including the interrupter for connecting the transformer primary to the low voltage source, thereby inducing a voltage in the transformer secondary in accordance with said physical value, a high-frequency oscillatory circuit connected between the anode of the valve and said secondary means for controlling the frequency of said oscillatory circuit, and a transmitting circuit coupled to said oscillatory circuit, whereby the signal transmitted is controlled by said physical quantity.

5. In a signaling transmitter for recording the degree of moisture of a hygrometer, a thermionic generator valve containing a cathode, grid and anode, a low voltage direct current source for the cathode, a transformer and an interrupter, means connected to said interrupter and controlled by a physical quantity for varying the interrupter frequency as a function of said physical quantity, circuit means including the interrupter for connecting the transformer primary to the low voltage source, thereby inducing a voltage in the transformer secondary in accordance with said physical value, a high-frequency oscillatory circuit connected between the anode of the valve and said secondary means for controlling the frequency of said oscillatory circuit, and a transmitting circuit coupled to said oscillatory circuit, whereby the signal transmitted is controlled by said physical quantity.
